Application April 17, 1936, Serial No. 74,929

20 Claims. (Cl. 158—7)

This invention relates to heating devices, more particularly to devices adapted to be used with furnaces, and of the type using fluid fuel as a source of heat energy, and the object of this invention is to provide new and improved devices of these types.

In the drawings accompanying this specification and forming a part of this application, I have shown, for purposes of illustration, several forms which my invention may assume, and in these drawings:

Figure 1 is a vertical sectional view of one embodiment of my invention, parts being broken away and parts being shown in elevation.

Figure 2 is a horizontal sectional view corresponding substantially to the line 2—2 of Figure 1.

Figure 3 is a perspective view of a manifold used in the embodiment disclosed in Figures 1 and 2.

Figure 4 is a perspective view of a baffle plate, partially broken away and shown in section to more clearly illustrate its construction.

Figure 5 is a perspective view of a burner used in the embodiment of this invention.

Figure 6 is a vertical sectional view similar to Figure 1, but illustrating a different embodiment of the invention.

Figure 7 is a horizontal section corresponding substantially to the line 7—7 of Figure 6.

Figure 8 is a vertical sectional view of another embodiment of the invention, parts being broken away and parts being shown in elevation, this view corresponding generally to the line 8—8 of Figure 9.

Figure 9 is a horizontal sectional view, partly in elevation, corresponding substantially to the line 9—9 of Figure 8.

Figure 10 is a vertical sectional view corresponding substantially to the line 10—10 of Figure 9.

Figure 11 is a vertical sectional view similar to Figure 8, but illustrating still another embodiment of the invention, and

Figure 12 is a horizontal sectional view corresponding substantially to the line 12—12 of Figure 11.

The embodiment of the invention disclosed in Figures 1 through 5 is particularly suitable for use with a furnace 20, which has an ash-pit 21, and a fire-box 22, the ash-pit and fire-box here being only fragmentarily shown. The ash-pit 21 is offset with respect to the fire-box 22 to form a shoulder 23.

As here shown, a fuel supply pipe 24 extends

into the ash-pit 21, and is connected by an elbow 25 with an upstanding pipe section 26, the upper end of the latter being connected with manifold means 27, which in turn has connection with a burner member 28. The manifold means 27 comprise a plurality of connected individual manifolds 29, the number of manifolds used depending upon the amount of heat to be supplied. Inasmuch as all of the manifolds 29 are alike, only one will be described in detail.

The manifold 29 comprises an elongated chambered member preferably formed as by casting. The manifold 29, in transverse section, has a rounded lower wall 30, generally parallel vertical walls 31 and 32, a top wall 33, a wall 34 angularly extending from the vertical wall 31, spaced and generally parallel to the top wall 33, and a wall 35 connecting the angular wall 34 with the top wall 33. The vertical wall 31, as shown in Figure 1, stops short of the top wall 33. The construction of the manifold thus described provides two elongated troughs closed from communication with the exterior of the manifold by means of integral end walls 36 spanning the ends of the troughs to form chambers 37 and 38, and the end walls 36 are provided with screw-threaded apertures 39. The elongated chambers 37 and 38 communicate throughout their length, the chamber 37 being considerably smaller in cross sectional area than the chamber 38, and having its bottom wall 34 disposed above the bottom wall 30 of the chamber 38. The bottom wall 30 of the chamber 38 is also provided with a screw-threaded opening to receive the screw-threaded extremity of the fuel supply pipe 26. The vertical wall 32 is provided with a screw-threaded opening which may be used to connect the manifold 29 to another manifold 29, but in this instance the screw-threaded opening is closed by a plug 40. In usual practice, when it is desired to connect together a plurality of manifolds 29, coupling pipes 41 are threaded into apertures 39 of adjoining manifolds 29, and the outer apertures of the end manifolds are closed by means of plugs. 45 In use with the manifold 29, or a plurality of connected manifolds, it will be apparent that the enclosing walls of the fire-box 22 are preferably rectilinear in extent so as to better accommodate the heating structure.

Each manifold 29 is provided with means for mixing primary air with fuel supplied by the chamber 38, and as here shown two generally hemi-spherical hollow members 42 are associated with each manifold, preferably by casting 55

the members 42 integrally with the manifold. Each of the members 42 provides a mixing chamber 43, into which air is drawn through a plurality of arcuate openings 44 formed in the flat front face 45 of the respective member 42. Extending centrally from the front face 45 is an apertured boss 46, and disposed about the boss 46 and rotatably mounted thereon, is an adjusting plate 47, having arcuate openings formed therein corresponding to the openings 44 formed in the front face 45 of the hollow member 42. The adjusting plate 47 may further be provided with a peripheral flange engageable with the periphery of the front face 45, and may be held in any desired adjusted position by any well known means, one preferred means including a machine screw passing through an arcuate slot in the adjusting member and threading into a screw-threaded aperture formed in an ear 48 integrally cast with the front face 45. The quantity of air being mixed with the fuel in the chamber 43 may be regulated by opening or closing the openings 44 in the front face 45 by proper movement of the adjusting plate 47. Communication between the mixing chamber 43 and the chambers 37 and 38 is effected by a nozzle orifice screw-threaded into the wall 35 and aligned with the axis of the mixing chamber 43.

30 A burner member 28 is adapted to cooperate with each mixing chamber 43 of the manifold 29, and as best shown in Figure 1, the burner member 28 comprises a tubular portion 49, having an extremity 50 fitting within the aperture formed in the boss 46 of the member 42, and held in position by means of a set screw 51 threaded into and passing through a wall of the boss 46. Inserting movement of the extremity 50 is limited by a shoulder spaced inwardly on 40 the tubular portion 49. The other extremity of the tubular portion tapers gradually to a widened part 52, and at this part the burner member is provided with an upwardly extending burner mouth 53, which as best shown in Figure 5, is generally rectilinear and elongated in a plane transverse to the axis of the tubular portion 49, and the burner mouth 53 tapers as it extends upwardly to provide a narrow elongated burner opening 54. To better describe the burner mouth, a face view would appear to be wing-shaped or generally V-shaped.

55 Spaced from the burner mouth 53 is an upstanding ear 55, provided with a screw-threaded aperture 56, and disposed between the burner mouth 53 and the ear 55 is a transversely extending rectilinear elongated ledge 57. The ledge 57 is an integral part of a channel shaped member 58, the latter member having an integral ledge 59 similar to and spaced from the ledge 60 57, and a web 60 extending downwardly from the ledge 57 and integrally connecting the ledges 57 and 59. Extending upwardly from the ledge 57, generally in line with the web 60 is a pair of abutments 61, and projecting from the burner mouth towards the ear 55 is a lug 62 having an inclined face 63 spaced from the ear 55.

65 Carried by the burner member 28 is a baffle means 64, comprising a pair of spaced plates 65 and 66, integrally connected at their longitudinal 70 ends by end walls 67 and 68 to form an elongated rectangularly shaped chamber 69, as best shown in Figure 2. Referring particularly to Figure 4, it will be noted that the wall 65 projects somewhat below the wall 66 to provide a projecting leg 70. The wall 66, at its lower extremity, is

provided with an angularly extending ledge 71, and at its upper extremity with a curved lip 72 partially overhanging the upper portion of the chamber 69. The end walls 67 and 68 extend only the length of the wall 66, the wall 67 being provided with a tongue 73, and the wall 69 being provided with a groove 74, the tongue and groove construction providing for interconnection with adjoining baffle means 64.

As best shown in Figure 1, the leg 70, of a baffle means 64, is disposed within the space defined by the inclined face 63 of the lug 62 and the adjacent face of the ear 55, the leg 70 resting on the top surface of the ledge 57. It will be noted that the space provided by the face 63 and the ear 55 is considerably greater than the thickness of the leg 70. To hold the baffle means in a desired position, a bolt 75 is threaded into the threaded aperture 56 of the ear 55, and proper manipulation of the bolt 75 will adjust the inclination of the respective baffle means 64 with respect to the enclosing wall of the fire-box 22 and also with respect to the burner mouth 53. As shown in Figure 1, the burner mouth 53 is provided with a projecting lug 76 to properly space the burner mouth from the wall of the fire-box 22.

In practice, the required number of manifolds 29 are assembled in the ash-pit 21, with the proper number of burner members 28 and baffle means 64, and the fuel supply conduit 24 is connected to the elbow 25. The elbow 25 is provided with a downwardly extending internally threaded tubular part 77, which screw-threadedly engages a screw-threaded rod 78 forming a part of a standard means 79. The standard means 79 further includes a foot 80, provided with an elongated tubular part having a screw-threaded aperture 81 which receives the lower end of the rod 78, and provides for vertical adjustment of the entire 40 heating device with respect to the furnace 20.

Referring to Figures 2, 4, and 5, it will be noted that the lateral extent of the walls 65 and 66 is substantially equal to the lateral extent of the channel 58, so that one burner member 28 and one baffle means 64 will constitute a unitary assembly. If only one manifold 29 is used, the apertures 39 are plugged and the fuel conduit is connected to the aperture in the bottom wall 39, and a burner member 28 is properly connected to each of the bosses 46 of the manifold 29. The baffle means 64 are then disposed in proper relation with the burner members 28, with the adjacent tongue and groove formed thereon in mating relation. One end of a plate 82 is then bolted to the ledge 59, the other end bearing against the abutment 23 formed on the furnace 20. Another plate 83 is disposed so as to have its one end carried by the ledge 71 of the baffle means and its other end carried by an abutment on the furnace, or by ledges formed on baffle means disposed at the other side of the furnace. The plates 82 and 83 separate the furnace into a lower compartment and an upper compartment, and passage of air from the lower compartment to the upper compartment is effected only by the passage through the baffle means 64.

From the foregoing description it will be evident that in operation of the furnace, primary air will be mixed with the fuel, which in this particular instance is gas, in the mixing chambers 43 associated with the manifolds 29, and this mixture is burned at the burner opening 54. Secondary air will be drawn upwardly from the ash-pit 21, and escapes only through the cham- 75

bers 69 formed in the baffle means 64. This secondary air will be heated by passage through the chambers 69, for the reason that the baffles 64 are disposed within the extremely heated range 5 of the flame issuing from the burner opening 54, and this air will be directed into the area of the flame by the lips 72 and will readily combine with any unburned gases at the tip of the flame to form a combustible mixture that will ignite 10 and furnish further heat, and also produce combustion relatively unaccompanied by unburned gases and undesirable soot. Also, by reason of the passage of air through the chambers 69, the baffle means 64 will not become overheated, and 15 cheaper and lighter material may be used to construct these baffle means.

Because of the particular construction of the burner opening 54, the flame issuing therefrom will be in the shape of a narrow elongated sheet, 20 and heat energy from this flame will be deflected towards the fire-box by reason of the adjacent disposition of the inclined baffle means 64. It will be apparent that suitable pilot burner means (not shown) may be used to ignite the burner 25 members 28.

When the valve (not shown) controlling the flow of fuel is turned to off position, the flame at the burner mouth 54 is prevented from flashing back to the manifold chamber 38 and fuel 30 supply conduit 24 by reason of the interposition of the vertical wall 31 in the passage normally traversed by such a flash back flame. It will be appreciated that the vertical wall 31 interrupts such flash back, and thereby avoids a dangerous 35 condition common to the ordinary type of burner. In addition, air which may enter the burner opening 54 and the mixing chamber openings 44 is prevented from entering the manifold chamber 38 and supply conduit 24 when the fuel control 40 valve is in off position, because the air will first enter the chamber 37 and settle to the bottom of the chamber and be trapped therein for the reason that the air is heavier than the fuel gas commonly used, and will displace this gas in the 45 chamber 37. The air in the chamber 37 forms an air seal which seals the orifice opening in the mixing chamber 43, and prevents any gas remaining in the chamber 38 or conduit 26 to pass to the mixing chamber 43; thus, after the gas in 50 the burner 28 is consumed, the flame cannot flash back to the mixing chamber, for the reason that there will be no gas in this mixing chamber.

Referring to the embodiment disclosed in Figures 6 and 7, the manifold means herein shown 55 comprises a manifold 84 in some respects similar to the manifold 29, in that chambers 85 and 86 and mixing chambers 87 are provided which are similar to the chambers 37 and 38, and mixing chambers 43, heretofore described. As before, the chamber 85 is disposed on one side of the chamber 86, but in this embodiment a chamber 88, similar to the chamber 85 is provided on the other side of the chamber 86, and the chamber 88 communicates with a mixing chamber 89 as 60 before. Therefore, from the foregoing description, it will be obvious that the construction on one side of the center line of the manifold is similar to that on the other side, and in this instance, the manifold 84 is provided with pairs of 65 axially aligned mixing chambers 87 and 89, which have connections to burner members 28a and baffle means 64a in the same relation as described in connection with the embodiment disclosed in Figures 1 through 5. In this embodiment, the chamber 86 receives the fuel from a supply con-

duit 24a, as before described in connection with the embodiment shown in Figures 1 through 5, and the chamber 86 supplies fuel to both sets of mixing chambers 87, 89. The manifold 84 and the entire heating structure carried thereby may 5 be adjusted longitudinally of the furnace by a standard means 79a.

The embodiment disclosed in Figures 8 through 10 comprises a manifold 90, arcuate in plan view, and used particularly in furnaces having a non-rectangular fire-box. The manifold 90 provides a generally closed chamber 91, which is locally interrupted on the outer wall at the upper extremity thereof at spaced points 92. Communicating with the interrupted parts 92 of the outer wall of the chamber 91, are radially extending chambered housings 93, integrally cast with the manifold 90, and completely enclosing the interrupted parts 92. Extending radially from the 15 housings 93, and cast integrally therewith, are semi-spherical chambered members 94, which have their mixing chambers 95 communicating with the interior of the chambered housings 93 through orifice nozzles 96. The chambered members 94 are provided with openings and bosses 20 similar to the members hereinbefore described, and the amount of air admitted to the mixing chambers 95 is regulated by apertured adjusting plates as before.

As best shown in Figure 9, the manifold 90 is 25 provided with four radially extending mixing chambers 95. The ends of the manifold are provided with apertured ears 97 which may be secured to suitable connecting means to hold the manifold 90 to the walls of the furnace, or to 30 another manifold 90. As before, the chamber 91 receives its fuel from a supply conduit 24b, and the conduit and the entire burner mechanism may be adjusted longitudinally of the furnace by 35 a standard means 79b. If more than one manifold 90 is used, fuel may be supplied to the other manifold 90 by a suitable connection with the supply conduit 24b and the other manifold may be adjusted by the use of a standard means similar to the standard means 79b. In some instances, it may be desirable to run a conduit between the inner walls of the manifolds to be connected, and for this purpose the inner walls are 40 provided with threaded apertures 98 which are normally closed by plugs 99.

In this embodiment the burner members 28b are somewhat similar to the burner members 23, but differ in the respect that the burner mouths 53b are arcuately shaped to conform generally to the shape of the fire-box. Also, the baffle 55 means 64b are similar to the baffle means 64, with the exception that in this case the baffle means 64b are laterally curved and are connected to each other by the tongue and groove joints to form an arcuate baffle device. The channel portions 58b, in this instance, cooperate with the channel portions of the adjacent baffle means to provide an arcuate channel to which the plate 82b is attached. The plate 83b rests on the arcuate shoulder formed by the ledges 71b of the cooperating baffle means 64b. The plates 82b and 83b, as before, separate the furnace into upper and lower chambers. In some instances, when the manifolds 90 do not form a complete annulus, suitable plate means (not shown) are secured to 65 the plates 82b and 83b to prevent the secondary air from following a course other than through the chambers in the baffle means 64b.

The operation of the construction shown in Figures 8 through 10 is generally similar to that 70 75

described in the embodiment disclosed in Figures 1 through 5, the interruptions 92 in the outer wall of the chamber 91 providing baffle means to prevent flash back of the flame from the burners 28b to the manifold chamber 91. Also, the chambered housings 93 provide pockets into which air infiltrating through the openings in the burners 28b and openings in the mixing chambers 95 may be trapped, to prevent such air from reaching the manifold chamber 91 and supply conduit 24b.

In the embodiment disclosed in Figures 11 and 12, the heating means herein disclosed are particularly adapted for use in furnaces having a circular and relatively small fire-box. The heating means comprises a manifold 100, forming a generally circular chamber 101. The chamber 101 has its outer wall, adjacent the upper extremity thereof, locally interrupted, as shown at 102. Communicating with each of the interrupted portions 102 is a radially extending chambered housing 103, integrally formed with the manifold 100, and integrally formed with each housing 103 is a semi-spherical chambered member 104, providing a mixing chamber 105. Communication from the manifold chamber 101 to the mixing chamber 105 is provided by means of an orifice nozzle 106.

Burner members 28c and baffle means 64c cooperate with each manifold chamber in a manner similar to that described in the embodiment of Figures 8 through 10. As in the aforesaid embodiment, the burner mouths 53c and the baffle means 64c are curved to generally conform to the circular shape of the fire-box.

Fuel is supplied to the manifold chamber 101 by means of a supply conduit 24c connected to a centrally located aperture in the bottom wall of the manifold chamber 101. As shown in Figure 12, the side wall of the chamber 101 is provided with a screw-threaded aperture 107 which is normally closed by a plug 108, and the fuel supply conduit 24c may in some instances be connected to the aperture 107.

The baffle means 64c, by reason of their tongue and groove connection, form a generally annular baffle to direct the flames issuing from the burner opening 54c towards the walls of the fire-box. As before, a plate 82c is secured to the ledges 59c of the channels 58c, and a plate 83c is supported by the ledges provided by the abutments 71c formed on the baffle means 64c. It will be appreciated that the baffle means 64c do not provide a complete annular construction, but if such construction is desired, the end baffle means 64c adjacent the plug 108 may be elongated laterally to close the gap. However, in this instance, the baffle means are all made of the same size and the gap formed is preferably disposed adjacent the door opening into the fire-box. To prevent secondary air from following a course other than through the chambers 69c in the baffle means 64c, a suitable plate 109 is secured to the plates 82c and 83c and closes the short circuiting air gap between the upper and lower chambers of the furnace.

The entire heating construction, including the supply conduit 24c, manifold 100, burner members 28c and baffle means 64c, is adjustable vertically of the furnace, as before, by an adjustable standard means 79c.

The operation of the embodiment disclosed in Figures 11 and 12 is similar to that described in connection with the embodiment disclosed in Figures 8 through 10, in that the walls of the

manifold chamber 101 adjacent the interrupted portions prevent flash back of flame to the manifold chamber 101, and the chambers in the housings 103 prevent air from infiltrating to the manifold chamber 101.

From the foregoing it will be apparent to those skilled in the art that the illustrated embodiments of my invention provide new and improved heating devices, and accordingly, accomplish at least the principal object of my invention. It further will be obvious to those skilled in the art that the illustrated embodiments of my invention may be variously changed and modified without departing from the spirit of my invention, or sacrificing all of the advantages thereof, and that accordingly, the disclosure herein is illustrative only, and my invention is not limited thereto.

I claim:

1. Heating means, comprising: a manifold, connectible to a source of fluid-fuel; a burner, communicating with said manifold; means for supplying primary air to the fuel delivered to said burner; baffle means for directing heat energy provided by the flame at said burner, said baffle means having a passage for supplying secondary air to a point adjacent the outlet of said burner, said passage being so constructed and arranged that said secondary air supply is independent of said primary air supply.

2. Heating means, comprising: a manifold, connectible to a source of fluid-fuel supply; means providing a mixing chamber, said chamber communicating with the interior of said manifold and receiving fuel from said manifold, and having means for supplying primary air to within said mixing chamber for mixing with the fuel within said mixing chamber; a burner, connected to said mixing chamber, receiving the mixture of fuel and primary air from said mixing chamber; and a member, constructed and arranged to direct the heat energy provided by the flame at the burner outlet, and be heated by this heat energy, said member having a conduit terminating above the burner outlet, for supplying secondary air, independent of said primary air supply, to the flame and the products of combustion rising from the flame, the secondary air being heated by its passage through said conduit and providing combustion of substantially all combustible material rising from the flame at the burner outlet.

3. Heating means, comprising: a burner, having spaced-apart abutments; a directing member, for directing heat energy provided by the flame at said burner, having a portion disposed between said abutments, and bearing upon said burner, said portion being of a thickness less than the spacing of said abutments, said member being so constructed and arranged to be normally urged to a position wherein said portion engages surfaces of each of said abutments; and adjustable means, constructed and arranged to engage said portion in certain adjusted positions, to urge said portion away from engagement with the surface of one of said abutments, and thereby change the position of said directing member.

4. Heating means, comprising: a burner, having spaced-apart abutments, one of said abutments having a screw-threaded aperture; a directing member, for directing heat energy provided by the flame at said burner, having a leg disposed between said abutments, and bearing

upon said burner, said leg being of a thickness less than the spacing of said abutments, and said member being so constructed and arranged to be biased to an inclined position wherein a portion generally overlies the burner mouth and said leg is in athwart relation with respect to said abutments; and an adjusting screw, threaded through said screw-threaded aperture, for engaging said leg in certain adjusted positions to move said leg out of engagement with the abutment carrying said screw, and move said directing member to a differently inclined position.

5. Heating means, comprising: a manifold device, providing a manifold chamber connectable to a source of fuel supply, a mixing chamber having an orifice opening establishing communication with said manifold chamber, and a trough interposed between said mixing chamber and said manifold chamber, and forming at least a part of the conduit through which fuel must pass when flowing from said manifold chamber to said mixing chamber.

6. Heating means, comprising: a manifold device, providing a manifold chamber connectable to a source of fuel supply, a mixing chamber having an orifice opening in a defining wall establishing communication with said manifold chamber, and a trough within said device and interposed between said mixing chamber and said manifold chamber, and forming at least a part of the conduit that fuel must flow through when passing from said manifold chamber to said mixing chamber, said trough comprising said defining wall and a wall spaced therefrom, said spaced wall extending above said orifice opening.

7. Heating means, comprising: manifold means, connectable to a source of fuel supply; mixing chamber means, receiving fuel from said manifold means, and being apertured to admit air to said mixing chamber so that the air may be mixed with fuel from said manifold means to form a combustible mixture; burner means, receiving the combustible mixture from said mixing chamber, and having a burner opening at which said combustible mixture is burned; and means, interposed between said mixing chamber means and said manifold means, constructed and arranged to provide an air seal when flow of fuel to said manifold means is interrupted, said air seal being positioned to interrupt fuel remaining in said manifold means from flowing into said mixing chamber means.

8. Heating means, comprising: manifold means, connectable to a supply of gaseous fuel that is lighter than air; mixing chamber means, having an orifice opening providing for the passage of fuel from said manifold means to said mixing chamber, and being apertured to admit air to said mixing chamber so that the air may be mixed with fuel from said manifold means to form a combustible mixture; burner means, receiving the combustible mixture from said mixing chamber, and having a burner opening at which said combustible mixture is burned; and trough means, interposed between said manifold means and the orifice opening in said mixing chamber means, constructed and arranged to provide an air seal when flow of fuel to said manifold means is interrupted, said air seal extending around said orifice opening to seal said opening, thereby preventing the lighter gaseous fuel remaining in said manifold means from flowing into said mixing chamber means.

9. Heating means, comprising: manifold means, adapted to receive a gaseous fuel that is

lighter than air; mixing chamber means, having an orifice opening providing for the passage of fuel from said manifold means to said mixing chamber, and being apertured to admit air to said mixing chamber so that the air may be mixed with fuel from said manifold means to form a combustible mixture; burner means, receiving the combustible mixture from said mixing chamber, and having a burner opening at which said combustible mixture is burned; and trough means, interposed between said manifold means and the orifice opening in said mixing chamber means, and comprising a lip so positioned that the gaseous fuel must flow upwardly from said manifold means, over said lip, and then downwardly to said orifice opening, the top of said lip being at a higher level than said orifice opening, said trough means filling with air when flow of fuel to said manifold means is interrupted, thereby providing an air seal extending above said orifice opening to seal said opening, whereby the lighter gases are prevented from flowing downwardly to said orifice opening.

10. Heating means, comprising: a manifold, connectable to a source of fuel supply; mixing chamber means, having an opening providing for the passage of fuel from said manifold to said mixing chamber, and being apertured to admit air to said mixing chamber to form a combustible mixture; burner means, receiving the combustible mixture from said mixing chamber, and having a burner opening at which said combustible mixture is burned; and separate baffle means, movable with respect to said burner opening, directing the heat energy provided by the flame at the burner opening, and being heated by this heat energy, said baffle means being hollow and open at the bottom and the top, and the top being positioned above the burner opening, whereby air is drawn inwardly of the bottom of said baffle means and passes through said hollow baffle means and is heated, and passes outwardly at the top and into the path of the products of combustion rising from the burner opening, thereby effecting substantially complete combustion.

11. A furnace, comprising: a fire-box; manifold means, connectable to a source of fuel supply; means, providing a mixing chamber communicating with said manifold means, and having a regulatable opening through which primary air may pass to be mixed with the fuel in said mixing chamber; burner means, communicating with said mixing chamber, and having a burner opening positioned adjacent the defining wall of said fire-box; chambered baffle means, extending upwardly with respect to said burner opening, for directing the heat energy from said burner opening toward said defining wall, said baffle means being open at its bottom and top and having its top above the burner opening, so that secondary air may pass through said baffle means and into the path of the products of combustion rising from said burner opening; and plate means, so constructed and arranged that air rising from the lower portion of said fire-box may pass to the opening in said mixing chamber means, or to the chamber of said baffle means independently of said mixing chamber.

12. Heating means, comprising: burner means, connectable to a source of fuel supply, having burner opening means adapted to form an elongated flame; and baffle means, movable relative to said burner means, and positioned to extend above the opening means of said burner means, having a conduit through which air may pass,

- said conduit terminating above said burner opening means, and said baffle means having directing means adjacent the termination of said conduit, constructed and arranged to direct the air 5 passing through said conduit in an elongated stream into the path of the products of combustion rising from said burner opening means.
13. Heating means, comprising: a single casting, providing an elongated manifold chamber 10 adapted to be connected to a source of fuel, and providing also a plurality of hollow bell-shaped portions spaced-apart along the length of said manifold chamber, each bell-shaped portion being closed by a generally plane wall having openings adapted to be controlled by a movable shutter, and each of said walls having means for receiving the end of a burner tube, each of said bell-shaped portions communicating with said manifold chamber, and forming a mixing chamber 15 20 wherein fuel from said manifold may be mixed with air admitted through the openings in the respective wall.
14. Heating means, comprising: a single casting, providing an elongated manifold chamber 25 adapted to be connected to a source of fuel and providing also a plurality of hollow bell-shaped portions projecting from opposite sides of said manifold chamber, each bell-shaped portion being closed by a generally plane wall having openings adapted to be controlled by a movable shutter, said wall having means for receiving the end 30 of a burner tube, and said bell-shaped portion communicating with said manifold chamber, and forming a mixing chamber wherein fuel from 35 said manifold chamber may be mixed with air admitted through the openings in said wall.
15. In combination: a fire-box; burner means, so constructed and arranged that the flame at the opening of said burner means is arranged in a line following the defining wall of said fire-box; and directing means, positioned adjacent said burner means, comprising a plurality of members, each being chambered and open at the bottom and top for the passage of air through 40 the chambers, said members being arranged side edge to side edge, and each member having a tongue at one side edge and a groove at the other side edge, the tongue of one member fitting into the groove of an adjacent member.
- 50 16. In combination: a fire-box; a plurality of burners, each having an elongated opening, said burners being so positioned that the burner openings are arranged in a line following the defining wall of said fire-box; and directing means, positioned adjacent said burner means, comprising a plurality of rectangularly-shaped members relatively narrow in width, each being hollow to form a chamber extending substantially to the edges of said member, and open at the top and bottom for the passage of air through the chamber, the top of each member having a curved lip directing the air passing through the respective member in a direction toward the products of combustion rising from the adjacent burner open- 55 60
- ing, said members being arranged side edge to side edge to extend substantially in line with the burner openings, each member having a tongue at one side edge and a groove at the other side edge, the tongue of one member fitting into the groove of an adjacent member.
17. Heating means, comprising: a unitary body, having a first portion providing a manifold chamber adapted to be connected to a source of fuel, and having also at least one hollow bell-shaped portion projecting from said first portion and a wall closing the mouth of said bell-shaped portion, said wall having an opening, and having also means for receiving the end of a burner tube, and the interior of said bell-shaped portion communicating with said manifold chamber and forming a mixing chamber wherein fuel from said manifold chamber may be mixed with air admitted through the opening in said wall.
18. Heating means, comprising: a single cast- 20 ing, having an integral first portion providing a manifold chamber adapted to be connected to a source of fuel, and having also at least one integral hollow bell-shaped portion projecting from said first portion and an integral wall clos- 25 ing the mouth of said bell-shaped portion, said wall having an opening, and having also means for receiving the end of a burner tube, and the interior of said bell-shaped portion commun- 30 icating with said manifold chamber and form- 35 ing a mixing chamber wherein fuel from said manifold chamber may be mixed with air admitted through the opening in said wall.
19. Heating means, comprising: a unitary body, having an arcuate first portion providing an 35 arcuate manifold chamber adapted to be connected to a source of fuel, and having also at least one hollow bell-shaped portion projecting from said first portion, and a wall closing the mouth of said bell-shaped portion, said wall hav- 40 ing an opening and having also means for receiving the end of a burner tube, and the interior of said bell-shaped portion communicating with said manifold chamber, and forming a mix- 45 ing chamber wherein fuel from said manifold may be mixed with air admitted through said wall opening.
20. Heating means, comprising: a unitary body, having an annular first portion providing an annular manifold chamber adapted to be connect- 50 ed to a source of fuel, and having also a plurality of hollow bell-shaped portions projecting generally radially from said annular first portion, the mouth of each bell-shaped portion being closed by a wall having an opening through 55 which air may be admitted, said wall having also means for receiving the end of a burner tube, the interior of each bell-shaped portion communicating with said manifold chamber, forming individual mixing chambers wherein fuel 60 from said manifold may be mixed with air admitted through the opening in a respective wall.

CHARLES L. BRYANT.
